BAND FOR GARMENTS

Harry Hardie, Baltimore, Md., assignor to The Nobelt Company, Baltimore, Md., a corporation of Maryland

Application April 15, 1950, Serial No. 156,185

1 Claim. (Cl. 2—237)

1

This invention relates to garment belts or bands, and more particularly to elastic garment belts of the type which are sewn onto a garment during manufacture and form an integral part of the garment.

Body openings of garments, such as torso or leg openings, are often provided with an elastic band or belt sewn to the edge of the opening for holding the garment in position on the wearer. The elastic band may extend either for only a portion of the length of the opening or may extend completely about the opening and have its ends united to form an endless band surrounding the waist or limb of the wearer.

Such elastic bands are sometimes formed of a strip of thin, elastic sheet-rubber covered with a textile sheath, the rubber and sheath being united and held in place on the garment by parallel rows of stitching penetrating the rubber strip. The garment band of the present invention is 15 of this type.

In the form shown of the present invention, an outer strip or sheath of woven textile material covers the outer surface of the rubber strip, the longitudinal edges of the sheath being folded closely about the edges of the rubber strip. The inner side of the rubber strip (towards the body of the wearer) is covered by a knitted textile sheath, the inner sheath being substantially co-extensive with the outer sheath and the longitudinal edges of the inner sheath being folded inwardly upon themselves to form hems along the top and bottom of the inner sheath. This band is assembled onto an edge of the garment, which is preferably of knitted material, during the manufacture thereof; the edge of the garment material being interposed between the inner sheath and the rubber strip and encompassing outer sheath. The band is united by three or more parallel rows of stitching extending longitudinally of the band.

Among the objects of the present invention are to provide an improved elastic garment band which is particularly suited for a garment formed of knitted material, which has a pleasing appearance, which is very comfortable to the wearer; and to generally improve garment bands of the type described.

Further objects, and objects relating to details and economies of manufacture and use, will more definitely appear in the detailed description to follow.

My invention is clearly defined in the appended claim. Where parts are, for clarity and convenience, referred to on the basis of their oriented position shown in the accompanying drawing, no limitation as to positioning of the entire structure is to be implied, since it will be understood that the entire structure may be used in any position depending on its mounting on the garment. Also, in both the description and the claim, parts at time may be identified by specific names for clarity and convenience, but

such nomenclature is to be understood as having the broadest meaning consistent with the context and with the concept of my invention as distinguished from the pertinent prior art. The best form in which I have contemplated applying my invention is illustrated in the accompanying drawing forming part of this specification, in which:

Fig. 1 of the drawing is an elevation of the outside of a garment having a band in accordance with the present invention, portions of the garment and band being broken away to show details of construction.

Fig. 2 is an enlarged, somewhat diagrammatic cross section of the garment and band taken on the line 2—2 of Fig. 1.

Fig. 3 is a view similar to Fig. 1 of a second form of the invention, in which the outer sheath is formed of bias-cut fabric.

Referring now to the drawings, the elastic band 10 of the present invention is particularly adapted for use as an elastic waistband for men's knitted pajamas or shorts, in which instance it is applied to the upper edge of the knitted garment material 11. It is well suited for use as an endless elastic band formed by permanently joining the ends of the band, as in the so-called "boxer" shorts, sufficient stretch being provided in the band and garment for putting on and taking off the garment. The garment material 11 preferably has a substantial stretch in the direction of the band 10 so as to permit stretching of the band and yet not have any substantial shirring of the upper edge of the garment material when the band is in relaxed or unstretched condition.

The elastic band 10 is formed of an outer textile sheath 12, an inner textile sheath 14, and a strip of thin, elastic sheet-rubber 15, which are assembled onto the edge of the garment material 11 and united by stitching as will be described. The outer textile sheath 12 is formed of woven textile material. In the garment band shown in Fig. 1, the outer sheath 12 is square cut, while in the second form shown in Fig. 3, the outer sheath is bias cut, the bands otherwise being similar. The outer sheath 12 covers the outer surface of the rubber strip 15.

The rubber strip 15 is a thin strip of elastic sheet-rubber (including rubber-like material) 50 preferably having a width when unstretched in the order of an inch to an inch and a half and suitable thickness to provide the desired tension of the band when in position on the wearer, which tension is varied depending on the weight of the garment to be supported. The edges 13 of the outer sheath 12 are folded over the top and bottom edges of the rubber strip 15 so as to encompass and more or less confine the rubber strip, as will be explained.

The inner textile sheath 14 is preferably formed of knitted textile material having a substantial stretch in the direction of the band 10 in order

to provide for stretch of the band and still not be substantially shirred when the band is in unstretched condition. Thus, there is no substantial shirring of the inner sheath when the garment is in position on the wearer and the soft, flexible knitted material forms a comfortable, relatively smooth body-engaging surface of the band 10. The inner sheath 14 is substantially coextensive with the outer sheath 12, covering the inner surface of the rubber strip 15 and having its edges folded in to form hems along the upper and lower edges of the sheath.

The outer sheath 12, inner sheath 14, and rubber strip 15 are held in assembled relation on the edge of the garment material 11 by rows 16 of parallel stitching, preferably four in number, running lengthwise of the band. The top and bottom rows 16 of stitching penetrate the outer sheath 12, the folded-over edges 13 of the outer sheath, the rubber strip 15, and the folded-over or hemmed portion of the inner sheath 14. The lower row of stitching also penetrates the edge of the garment material which is interposed between the lower folded-over edge 13 of the outer sheath, and the rubber strip 15 on one side, and the inner sheath 14 on the other side. In addition, one or more rows 16 of stitching, preferably two in number, penetrate the outer sheath 12, rubber strip 15, and inner sheath 14 between the top and bottom rows of stitching. Preferably, the garment material is penetrated by the next to the bottom, as well as the bottom, row 16 of stitching.

The band 10 is preferably assembled on the garment material 11 at the sewing point and then sewn while in stretched condition. The outer sheath 12, inner sheath 14, and rubber strip 15 are fed to the garment in strip form through suitable guides and folders, the rubber strip, inner sheath, and edge of garment material being stretched a predetermined amount, and the outer woven sheath not being substantially stretched, particularly if square cut rather than bias cut.

After assembly at the sewing point, the band is sewn when in stretched condition by a multiple-needle machine so as to insert all the rows 16 of stitching simultaneously and produce stitches which coincide (the needle penetrations of the band opposite one another), thus producing a uniform shirring of the band. Preferably, a straight stitch is used, having a length when stretched of about ten stitches to the inch.

By sewing the band 10 when in stretched condition, it is not necessary to use elastic or zig-zag stitches, and the band may subsequently be stretched to the amount that it was stretched when sewn without unduly stressing the stitching. Further, the outer sheath 12, which is sewn in flat condition, or unshirred, limits the stretch of the band, particularly if a square-cut sheath is used.

Another feature of the band of the present invention is that, when stretched, the rubber strip 15 contracts somewhat in width. Thus, by folding the edges 13 of the outer sheath 12 about the rubber strip when it is in somewhat narrower stretched condition, the strip will expand laterally when relaxed so as to completely fill the folded-over edges of the outer sheath and stiffen these edges to hold them against folding back against the face of the band along the top and bottom rows of stitching. This arrangement gives an outer sheath of improved appearance, facilitates ironing of the garment if desired, and stiffens the outer sheath so as to make ironing thereof unnecessary.

In the second form of the invention, which is shown in Fig. 3, the outer sheath 17 is formed from a strip of woven material cut on the bias so that the entire band may expand and contract somewhat in width with the rubber strip 15 as tension on the band is varied. The other parts of the band of Fig. 3 are similar to the band of Fig. 1 and assembled in a similar manner.

If the outer sheath 12 is square cut from woven material as in Fig. 1, there is no substantial lateral stretch of the sheath as it is relaxed from stretched condition, and the rubber strip 15 is inwardly arched to form a series of pad-like flexible corrugations. However, if the outer sheath is bias cut from woven material as in Fig. 3, the lateral stretch of the sheath (which is not substantially limited by the inner sheath of knit material) will permit the rubber strip 15 to remain flat, the outer sheath still confining the strip sufficiently to reinforce the outer sheath, particularly the edges thereof. In the latter instance, the band 10 expands laterally somewhat when relaxed from stretched condition, the rubber strip remaining generally flat rather than arching inwardly between the rows of stitching.

The woven outer sheaths 12 or 17 may be cut from material forming a pleasing contrast to the knit garment material 11. In addition, the shirring of the outer sheath by the stitches 16 gives a very pleasing appearance to the band. At the same time, the inner sheath 14 and the garment material are not substantially shirred and remain smooth and comfortable to the wearer.

I claim:

An elastic band for a garment, comprising: a strip of thin elastic sheet-rubber, an outer woven textile sheath covering the outer surface of the rubber strip with the edges of said sheath folded closely over the edges of the rubber strip and more or less confining the edges of the rubber strip against lateral expansion when the band is in unstretched condition, an inner textile sheath covering the inner surface of the rubber strip, the edges of the inner sheath being folded inwardly to form hems, and the inner and outer sheaths being approximately coextensive, an edge of garment material interposed between the inner sheath and the assembly of rubber strip and outer sheath, and a plurality of parallel rows of stitching extending longitudinally of the band, such rows of stitching being sewn with the rubber strip in longitudinally stretched condition, said stitching including top and bottom rows of stitching passing through the outer edge portions of the outer sheath, the rubber strip, the folded-over portions of the outer sheath, and the hems of the inner sheath, the bottom row of stitching additionally passing through the garment material, and the stitching also including at least one intermediate row of stitching passing through the outer sheath, the rubber strip, and the inner sheath.

HARRY HARDIE.
